Primary Examiner — Mimosa De(74) Attorney, Agent, or Firm — Theodore M. Magee; Westman, Champlin & Kelly, P.A.(57) CLAIM

The ornamental design for a chair, as shown and described.

DESCRIPTION

FIG. 1 is a perspective view of a chair;

FIG. 2 is a side view thereof, the opposing side being a mirror image;

FIG. 3 is a front view thereof;

FIG. 4 is a rear view thereof; and,

FIG. 5 is a top view thereof.

The broken lines shown in the drawings are included for purposes of illustrating portions of the chair and form no part of the claimed design.

1 Claim, 5 Drawing Sheets(56)
